UNITED STATES PATENT OFFICE.

WILLIAM HUGHES, OF PHILADELPHIA, PENNSYLVANIA, ASSIGNOR TO THE HESS-BRIGHT MANUFACTURING COMPANY, A CORPORATION OF DELAWARE.

SELF-OPENING TOOL HOLDER.

Application filed December 22, 1920. Serial No. 432,403.

To all whom it may concern:

Be it known that I, WILLIAM HUGHES, a citizen of the United States, residing at Philadelphia, in the county of Philadelphia and State of Pennsylvania, have invented 5 certain new and useful Improvements in Self-Opening Tool Holders, of which the following is a specification, reference being had therein to the accompanying drawing.

10 This invention relates to tool holding, operating and controlling mechanism, and has particularly for an object the actuation of a pair of cutters in a metal working machine, whereby these may be concurrently held in 15 their operative position upon opposite sides of a workpiece during the cutting movement, and released and held in idle positions during the return movement.

10 In the drawings accompanying this specification one practicable embodiment of the invention is illustrated, in which drawings,

Figure 1 shows in elevation a portion of a machine tool equipped with my improved tool actuating and controlling device.

25 Fig. 2 is an elevational view of the major portion of the device, looking at this portion from the left-hand side in Fig. 1, and on a larger scale.

Fig. 3 is a plan view of a portion of the 30 device shown in Fig. 2, the bed plate of the machine, however, being omitted.

Fig. 4 is a view somewhat similar to Fig. 3, but showing the top plate removed, the better to illustrate the construction of the 35 toggle mechanism and the pivotally mounted tool holders.

Figs. 5 and 6 are details of construction 40 showing various operative positions of certain parts, these latter figures showing the same elevation and being on the same scale as Fig. 1, and

Fig. 7 is a sectional detail taken on a plane at about the line 7-7 of Fig. 4, but shown as of the same scale as Fig. 1.

45 My improvement is intended for use on a machine in which the tools have a reciprocating movement in relation to the work, and are operative in the forward excursion and pass idly over the work in their recessional movement. It has been found desirable, especially in metal working machines, when the work performed by the tool has been a finishing cut, to move the cutting portion of the tool into a position out of the 50 path of movement of the work, since it is

obvious that after the tool has completed its cutting operation and moved past the work it will naturally spring slightly inwardly of the plane of the cut surface, and the tool in its recessional movement, which is generally faster than the cutting movement, then has the effect of scoring the otherwise finished surface of the work. Assuming that the cutters move in a straight line reciprocatory path and the work rotates, 60 the finished surface produced by the cutter is an even spiral of narrow convolutions, and the scoring of the cutters on the return movement is a deeper cut spiral of wide convolutions. Such marring of the finished surface necessitates that the next operation to which the work is subjected be more extensive than is otherwise necessary. In another aspect of the situation the finishing tools are not set to remove as much of the metal as 65 they otherwise would but for this scarring or marring. According to my invention, however, the tools, represented in the drawing as *x* and *y*, are separated at the completion of their forward traverse of the work-piece A, that is, in a movement toward the right in the drawings, so that upon their recession they clear the surface of the work-piece over which they have performed their 70 operation, and are, after being cleared of such work, again brought into their operative or cutting position in the interval during which one workpiece is removed and another placed at the working point of the machine. In some instances one of the tools, 75 *x* and *y*, may be employed for steadyng the workpiece during the cutting operation of the other. In most instances, however, both these tools are cutting tools, and for simplicity in this description are so referred to 80 without, however, limiting the scope of the claims to mechanism in which both tools are of necessity simultaneously cutting the workpiece. The tools *x* and *y*, are respectively mounted upon toggle controlled pivotally mounted tool holders 7 and 8. These 85 tool holders are moved into and out of working position by means of toggle links 9 and 10, which are caused to automatically function upon the reciprocation of the mechanism carrying the tool holders. In the present illustration the general casing or housing member 11 for these tool holders is 90 adjustably mounted in a well known manner upon a slide or carriage 12 adapted for auto- 100 upon a slide or carriage 12 adapted for auto- 105 upon a slide or carriage 12 adapted for auto- 110

matic reciprocation upon the framework 13 of the machine upon which the workpiece A is chucked. The carriage 12 moves, in the present illustration, in a horizontal direction 5 from side to side as indicated by the double headed arrow in Figure 1. The upper portion or housing 11 of the tool holder is shown pivotally connected to the base portion 14, which in turn is fastened by means of T- 10 bolts to the slide or carriage 12. The pivot pin is illustrated at 15. The pivot engaging portion 16 of the housing is shown pinned, by a pin 17, to the pivot pin. The tool holder casing 11, in the illustration, is 15 shown having a pivotal adjustment for raising and lowering the working point of the tools by means of an adjusting screw 18, and is moved laterally to effect the lateral position of the tools by means of suitable set 20 nuts 19, 20 carried on a screw threaded extension 21 of the pin 15 and engaging upon the opposite sides of a lug 22.

In the illustration the tool *y* is mounted 25 in a suitable socket formed in the forward end 23 of the tool holder 8. The tool is held in this socket for longitudinal adjustment by means of suitable set screws 24. The tool *x* is shown mounted in a suitable socket formed in a bit holder 25, the tools *x* and *y* 30 being frequently designated bits, which is carried by the forward end of the tool holder 7, and is adapted for adjustment transversely of the path of the tool movement. The tool *x* itself is adapted for adjustment longitudinally and is held in position by suitable set screws 28. There is shown a slot 26 in the bit holder 25 occupied by a suitable set screw 27. At the end of holder 25 opposite the bit seat is shown an actuator engaging 35 device, in the illustration a plate 48 held in position by a screw 49 and engaging collars on a screw 50. By the mechanism just described, the distance apart of the tools may be adjusted.

45 The tool holders 7 and 8 are provided with hubs or bosses 30 and 31 respectively, engaging suitably formed seats in the casing or housing of the device. The combined hub is shown provided with a taper bore in which 50 there is mounted a taper pin 32 serving, in certain movements of the device, as a fulcrum for the levers. This pin is shown provided with a screw threaded stem 33 and set nuts 34 whereby it may be adjusted for taking up slack and compensating for wear.

55 Each of the toggle links 9 and 10 is shown provided with rounding ends which fit into sockets having walls of more than 180 degrees, the socket for one end being formed 60 in the lever, and for the other end in the adjacent sides of a toggle link connecting and actuating block 35. The block is adapted to be pressed outwardly for releasing the toggles and moving the tools away from their 65 working position by means of a compression

spring 36 engaging against the inner end of the block 35 and against the longitudinally adjustable block 37. In the illustration the toggles are moved into alignment and the tools into working position by means of a 70 stationary adjustable abutment 38 carried by an adjustable head 39 supported on a bracket 40 secured to the machine frame 13. The rearward or idle movement of the device brings the block 35 against the abutment 38, as seen in Fig. 6, and by a continuation of its movement in this direction it compresses the spring 36 and moves the parts into the Figure 4 position. Whereupon the spring pressed detent 41, in the form of a 80 hook, passes beyond the end of the block 35, and holds this and the tool holders in their operative position and the spring 36 compressed. The detent 41 is shown so holding the block in Fig. 1.

85 Upon the completion of the cutting operation, the tools and their carrying devices continue to move forward, bringing a cam face 42, carried by a link 43, pivoted at 44, to the head 39, under a cam engaging stub 90 pin 35 carried by the detent 41, thereby forcing the detent upwardly against the pressure of its spring 46, and into such a position that it rises beyond the rear face 47 of the block 35 thereby releasing such block to the action 95 of the spring 36, whereupon the block is moved to the Figure 5 position, the toggle released, and the tools opened and moved to idle position, in most instances both tools are withdrawn to such positions that they 100 are free of the workpiece and run clear of the surface they have lately finished. A notch is shown cut in the upper surface of the block 35 so that an abutment face is provided for the engagement of the detent 41 105 whereby the outward or rearward movement of such block is limited by the detent.

110 It will be appreciated that the operation of the mechanism illustrated and explained in the foregoing description is continuous and automatic with the continuous and automatic movement of the machine upon which it is mounted. A wide range of adjustment is afforded for the tools in relation to the 115 position at which the workpiece is held, and at which the various parts are capable of adjustment for compensating inequalities and wear. Any further detailed description of the operation of the machine is doubtless unnecessary to those skilled in the art.

120 Altho but a single operative embodiment of my invention is shown in the drawings it will be understood that changes in details of construction may be made, to meet various requirements, within the scope of the 125 claims without departing from the spirit of the invention.

I claim as my invention:

1. The combination with a machine frame 130 provided with ways, of a carriage mounted

- for reciprocation thereon, a pair of tool holders mounted on the carriage and provided with tools located to simultaneously traverse the opposite sides of a piece of work, an actuator mounted on the carriage for moving the tool holders toward and from each other for placing the tools in operative and inoperative positions, and means mounted on the machine frame and located in position for automatically causing said actuator to function.
2. The combination with a machine frame provided with ways, of a carriage mounted for reciprocation thereon, a pair of tool holders pivotally mounted on the carriage in the form of levers, tools carried by the forward ends of the respective tool holders, an actuator mounted on the carriage for separating the rearward end of said tool holders to place the tools in operative position and for drawing said ends together for withdrawing the tools from the work, and means mounted on the machine frame and located in position for causing the actuator to function at the forward movement and at the backward movement of the carriage.
3. The combination with a casing, of a pair of tool holders mounted thereon, each of said tool holders being in the form of a lever and having a hub or boss member constituting a fulcrum, there being a suitably formed socket in the hub constituted by the two bosses, said hub being provided with a taper bore, a taper pin located in said bore and provided with means for moving it endwise for taking up slack, a tool carried by one end of each of the said levers, said tools being adapted for engaging the opposite sides of a piece of work, a toggle connecting the other ends of the said levers, and means normally tending to hold the links of the toggle in alignment and the tools locked at their operative positions.
4. The combination with a casing, of a pair of tool holders mounted thereon, each of said tool holders being in the form of a lever and having a hub or boss member constituting a fulcrum there being a suitably formed socket in the hub constituted by the two bosses, said hub being provided with a taper bore, a taper pin located in said bore and provided with means for moving it endwise for taking up slack, tools carried by one end of each of the said levers, said tools being adapted for engaging the opposite sides of a piece of work, a toggle connecting the other ends of the said levers, means normally tending to hold the links of the toggle in alignment and the tools locked at their operative positions, and automatic means for breaking the toggle and causing the tools to separate.
5. A self-opening tool comprising, a reciprocating body, a pair of cutters carried thereby and adapted to concurrently act upon opposite sides of a workpiece, means mounted on the carriage for positively moving the cutters into operative position and locking the same thereat, and means located in position in the path of movement of the said reciprocating body, and adapted to act upon the cutter moving means for automatically moving the cutters into operative position at the completion of the recessional movement of the body, and means located in position to automatically actuate the cutter moving means and open the cutters upon the completion of the excursion of the said body.
6. A self-opening tool comprising, a reciprocating body, a pair of cutters adapted to concurrently act upon opposite sides of a workpiece, a toggle connected with the cutters for closing and opening the same, a spring normally tending to move the toggle into open position, means active upon the toggle for compressing the spring and positively moving the cutters into operative position at the completion of the recessional movement of the said body, and means for automatically releasing the toggle to the influence of the said spring upon the completion of the excursion of the said body for opening the cutters.
7. The combination with a reciprocating carriage, of a pair of tool holders in the form of levers disposed longitudinally of the carriage, tools carried by the forward ends of the respective levers, a block disposed between the rearward ends of the levers and reciprocating longitudinally of the carriage, toggle links articulated to the block and to the respective levers and adapted upon its movement to cause the tools to approach and withdraw one from the other, and means for automatically causing said block to reciprocate upon the forward and backward movements of the carriage.
8. The combination with a reciprocating carriage, of a pair of levers pivoted to the carriage and disposed longitudinally thereof, said levers being provided at their forward ends with tool sockets, a block disposed between the rearward ends of the levers and reciprocating longitudinally thereof, a compression spring engaging said block and tending to move it rearwardly of the carriage, toggle links articulated to the block and to the respective levers and adapted upon its movement to cause the forward ends of the levers to approach and withdraw one from the other, a detent adapted when in one position to hold the block in a forward position with the toggle links in alignment, and when in another position to limit the movement of the block rearwardly under the influence of the spring, an adjustable actuator for engaging the block and moving the same forward upon the rearward movement of the carriage, and an adjustable actuator for engaging the detent

and moving it from the first mentioned to the second mentioned position upon the forward movement of the carriage.

9. A self-opening tool comprising a pair of levers of the first class, the forward ends of said levers being provided with cutters facing each other, a reciprocatory block mounted between the rear ends of said levers, and toggle links connecting the block with the levers, said block and levers having suitably formed sockets and the links having suitably formed ends whereby the reciprocation of said block causes the toggle links to positively move the levers in both directions.

10. The combination with a casing, of a pair of levers mounted thereon, cutters mounted at the forward ends of said levers and adapted to concurrently engage opposite sides of a piece of work, and each of said cutters being independently longitudinally adjustable upon its respective lever, and one of said cutters being movable trans-

versely of its lever, means for moving the cutter carrying end of the levers toward and from each other, a reciprocatory carriage, said casing being adjustably pivotally mounted on said carriage for raising and lowering the working points of the cutters, and means for adjusting the casing crosswise of the carriage for concurrently laterally shifting the working points of the cutters, the casing being provided with a downwardly disposed lug having a bore located transversely of the levers, an arbor located transversely of the carriage and disposed in the said transverse opening in the lug of the casing, means for longitudinally adjusting said arbor, means for locking the lug to the arbor, means for preventing the arbor from rotation, and an adjustable support for the rearward end of the casing.

In testimony whereof, I have affixed my signature hereto.

WILLIAM HUGHES.
